Inventor:
THOMAS RHODUS,
By Robert Burns, Atty.

UNITED STATES PATENT OFFICE.

THOMAS RHODUS, OF CHICAGO, ILLINOIS, ASSIGNOR TO THE MAGNIPHONE COMPANY,
A CORPORATION OF ARIZONA.

TELEPHONE HEAD-GEAR.

1,215,060.

Specification of Letters Patent.

Patented Feb. 6, 1917.

Application filed October 7, 1915. Serial No. 54,483.

To all whom it may concern:

Be it known that I, THOMAS RHODUS, a citizen of the United States of America, and a resident of Chicago, in the county of Cook, State of Illinois, have invented certain new and useful Improvements in Telephone Head-Gear, of which the following is a specification.

This invention relates to that type of telephone headgear or supports in which the holder is formed of semi-circular spring bands, and carries at one end an adjustable holding means for the telephone receiver and at the other end an opposed bearing pad or button.

And the present improvement has for its object to provide a simple and efficient structural formation and combination of parts, whereby a compact, nearly invisible and closely fitting formation of the holding means, and its adjustable connection with the resilient head bands, is attained, with an avoidance of any projections which might catch in the hair of the user or in other closely adjacent objects, the formation at the same time permitting of an independent movement of the telephone receiver to attain an accurate position, with relation to the ear of the user, all as will hereinafter more fully appear.

In the accompanying drawings:

Figure 1, is a perspective view, illustrating the general arrangement of parts in the present invention.

Fig. 2, is a detail section of the holding means of the telephone receiver and the adjustable connection of said means to the resilient head bands.

Similar reference numerals indicate like parts in both views.

Referring to the drawing, 1 designates the ordinary semi-circular spring head bands adapted to fit over the crown of the user's head. Said bands are preferably two in number and are arranged in adjustable separated relation as shown.

2 designates the usual bearing pad or button, pivotally attached, to one end of the head bands 1 in any usual and suitable manner.

3 designates a hub, preferably of a cylindrical form, and preferably slotted at one end to receive the ends of the head bands 1, opposite to the aforesaid bearing pad or button 2. Said bands and hub are pivotally

connected together by a transverse rivet or pin 4, as shown.

5 designates the yoke shaped holder of the present structure, preferably of the semi-circular form shown, having its flat side in alignment with the flat sides of the head bands, and provided with inturned end prongs 6, adapted for holding engagement in recesses or orifices, formed therefor in the opposite sides of the wall of a telephone receiver.

7 designates the attaching neck of the yoke shaped holder 5, preferably a separate cylindrical piece, slotted or recessed at the end to receive the central portion of the yoke body 70 and pivoted thereto by a transverse pin or rivet as shown. In the present improvement the attaching neck 7 is formed with a screw threaded shank 8 at its upper end, adapted for both turning and vertical adjustments in a screw threaded orifice 9, formed therefor in the lower end of the hub 3, above described. It is within the scope of this invention to reverse the location of the above described orifice and shank on the respective parts.

Having thus fully described my said invention, what I claim as new and desire to secure by Letters Patent is:

1. In a head gear for telephone receivers, 85 the combination of a head band having flat sides, a yoke having flat sides adapted for engagement with a telephone receiver, and intermediate adjustable means adapted to vertically align the flat side of said yoke with the flat side of one end of said head band, substantially as set forth.

2. In a head gear for telephone receivers, 95 the combination of a head band, a hub formed with a recess at one end for connection with said head band and provided with a central orifice in its other end, a transverse pin forming a pivotal connection between said hub and band, and a yoke adapted for engagement with a telephone receiver 100 and having an attaching neck formed with a shank for turning engagement in the hub orifice aforesaid, substantially as set forth.

3. In a headgear for telephone receivers, 105 the combination of a resilient head band, a hub formed with a slotted end for connection with said head band and provided with a central screw-threaded orifice in its other end, a transverse pin forming a pivotal connection between said hub and band and a 110

yoke adapted for engagement with a telephone receiver and having an attaching neck formed with a central screw-threaded shank for engagement in the screw-threaded orifice 5 of the hub aforesaid, substantially as set forth.

4. In a head gear for telephone receivers, the combination of a resilient head band having flat sides, and a yoke having flat 10 sides adapted for engagement with a tele-

phone receiver and attached to said head band, said yoke having inturned end prongs formed integrally with the yoke, the flat sides of the yoke being in the same plane as the sides of the prongs, substantially as set 15 forth.

Signed at Chicago, Illinois, this 4th day of October 1915.

THOMAS RHODUS.
